UNITED STATES PATENT OFFICE.

WILLIAM HENRY HART, OF GREEN BAY, WISCONSIN.

OIL-CUP.

1,367,471.

Specification of Letters Patent.

Patented Feb. 1, 1921.

Application filed October 8, 1919. Serial No. 329,426.

To all whom it may concern:

Be it known that I, WILLIAM H. HART, a citizen of the United States, residing at Green Bay, in the county of Brown and State of Wisconsin, have invented certain new and useful Improvements in Oil-Cups; and I do declare the following to be a full, clear, and exact description of the invention, such as will enable others skilled in the art 10 to which it appertains to make and use the same.

This invention relates to improvements in oil cups, more particularly to that type ordinarily used on cross heads and other parts 15 of locomotives.

The principal object is to provide a simple and practical oil cup especially constructed for use on machinery in which the vibration is sufficient to render the ordinarily 20 constructed oil cups practically useless.

Another object is to provide an oil cup in which the cover is so constructed and mounted on the receptacle, that it will invariably automatically seat itself properly.

25 A further object is to construct and mount a cover for an oil cup in such a manner that it may be used for adjusting the oil flow controlling valve.

With the above and other objects in view, 30 the invention consists of certain novel features of construction, and the combination and arrangement of parts as will be more fully described and claimed.

I attain these objects by constructing the 35 cups as illustrated in the accompanying drawings, in which—

Figure 1, is a vertical sectional view of the improved oil cup;

Fig. 2, is a sectional view taken on the 40 line 2—2 of Fig. 1, and

Fig. 3, a sectional view taken on the line 3—3 of Fig. 1.

Similar numerals of reference designate 45 similar parts throughout the several views.

Reference is now had to the drawings in which the receptacle 1 is shown as being of the ordinary construction and having a depending threaded nipple 2 for threaded engagement in an oil hole in a cross head or 50 other part of a machine. The receptacle is provided with a cover 3 of any preferred form, it being shown in the drawings substantially semi-elliptical in cross-section, although it may well be of a different shape.

55 While any suitable valve may be used for

regulating the flow of oil from the receptacle through the outlet of the nipple 2, I preferably construct a needle valve casing or hollow elongated body 4 provided at its lower end with a diametrically reduced 60 threaded nipple 5 which is screwed into a centrally disposed threaded socket in the bottom of the receptacle, said body having a bore of a uniform diameter from its upper end to a point substantially midway the 65 length of the body and at said point the bore 6 is slightly reduced to receive the small lower end 7 of the needle valve or screw valve 8. At a point adjacent the juncture of the body 4 and threaded nipple 5, the diameter of the bore is decreased to form a beveled seat 9, for the tapered lower end 7 of the needle valve.

For the purpose of admitting oil to the bore 6 of the body 4, two pairs of diametrically oppositely positioned openings 6a are provided, as shown in full lines in Fig. 3 and dotted in Figs. 1 and 2, this being the preferred, though not absolutely essential manner of accomplishing the desired result. 75

The needle valve is preferably, though not necessarily, of greater diameter at its upper end than at its lower end, said upper end being threaded to engage threads in the large upper end of the bore. 80

At a point above the upper end of the body 4, the diameter of the needle valve 8 is increased to form an annular shoulder 9' on the lower face of a head 10 which is provided on the extreme upper end with laterally directed angular ears 11, said ears being adapted for reception in a similarly shaped recess 12 in the lower face of the cover 3, so that the needle valve may be manually adjusted through rotation of said cover. 95 The above described connection between the cover and valve is the preferred form but it is understood that any other suitable means may be employed with good results.

The cover 3 is preferably formed with 100 studs or bosses 13 whose adjacent walls form the recess 12, said bosses having flat lower faces, upon which a pair of substantially L-shaped brackets 14 are riveted or otherwise fastened. Slidable vertically on the valve 105 body 4 is a plate 15, preferably stamped from a single piece of metal. An opening is formed in said plate to receive the valve body 4, and the metal forming the wall of the opening is bent at right angles to the 110

plate proper to form a guide flange 16, which serves to prevent canting of said plate. A pair of laterally oppositely directed substantially L-shaped arms are formed on said 5 plate, said arms and the aforementioned brackets 14 being connected by suitable link 17.

Abutting against the shoulder 9' of the head 10 is a plate or disk 18, which preferably has a depending flange on its periphery, said plate coacting with the lower plate 15 to compress a coil spring 19, which preferably surrounds the valve body 4 and through its expansive action retains the cover in 10 closed position. It is understood that although the enlarged head and the upper plate 18 are the preferred elements to act against the spring, I may employ any other suitable means.

20 For the purpose of assisting the coil spring in preventing accidental adjustment of the valve, I have provided a substantially inverted U-shaped spring 20, which is mounted in a transverse opening in the head 25 of the valve and has a portion of the arms frictionally engaging the receptacle or cup wall. This spring prevents vibration (of the guide rod or cross head upon which the cup is mounted) from causing the valve to 30 rotate and close the outlet.

Because of the frictional engagement between the elements 9' and 18, between the elements 15 and 19, and between the screw-threads of elements 4 and 8, caused by pressure of the spring 19, the latter may properly be termed yielding means for resisting accidental adjustment of the needle-valve or adjustable feed regulator 8. Similarly, the spring 20 may properly be termed 40 yielding means for resisting accidental adjustment of the needle-valve. It is obvious that these means coact for controlling the needle-valve and that this valve controls the springs 19 and 20 by securing them in their 45 operative positions. Either of the springs 19 and 20 will control the needle-valve 8 if the other spring becomes broken, but greater efficiency is obtained by their combined action.

50 When it is necessary to refill the cup with oil the cover is raised free from the head of the valve and is tilted or slid to one side of the cup whereupon oil may be readily poured into said cup. The needle valve 55 may be adjusted by employing either of two different methods. The first being to replace the cover, the head of the needle-valve automatically seating itself in the recess in in the lower face of the cover. The cover 60 may now be turned and with it will turn the needle-valve whereby the flow of oil is controlled.

The second method of adjusting the needle-valve is to turn it with the fingers 65 before the cover is replaced and when the

cover is in closed position it will lock the needle-valve against accidental movement.

From the foregoing description, taken in connection with the accompanying drawings, the construction and operation of the 70 invention will be readily understood without requiring a more extended explanation.

Various changes in the form, proportion and minor details of construction may be resorted to without departing from the 75 principle or sacrificing any of the advantages of the claimed invention.

I claim:

1. An oil cup comprising a receptacle having an inlet and an outlet, a rotary valve for 80 controlling said outlet, a cover for said inlet, means for holding the cover in normally closed position while permitting it to be moved upwardly and laterally off of said inlet and also permitting said cover to rotate 85 freely when in closed position, and a detachable interengaged connection between said valve and said cover when the latter is in its closed position, whereby said valve may be adjusted by rotating said cover. 90

2. In an oil cup, a receptacle having an inlet and an outlet, adjustable means operable to regulate the flow of oil through said outlet, a cover normally seated on said receptacle and closing said inlet while being engaged with said adjustable means and operable to adjust the latter, and means under control of said adjustable means for removably securing said cover in its closed 95 position. 100

3. In an oil cup, a receptacle having an inlet and an outlet, adjustable means operable to regulate the flow of oil through said outlet, a cover normally seated on said receptacle and closing said inlet while being engaged with said adjustable means and operable to adjust the latter, and yieldable means engaged with said adjustable means for resisting accidental adjustment while permitting easy manual adjustment of said 110 adjustable means. 105

4. In an oil cup, a receptacle, a removable cover therefor, a valve for permitting flow of oil from the receptacle, spring means for retaining the cover on the receptacle, and a 115 detachable connection between the cover and parts of the valve whereby rotary movement of the cover will adjust the valve.

5. In an oil cup, a receptacle, a removable cover therefor, a screw valve for permitting flow of oil from the receptacle, spring means for retaining the cover on the receptacle, and interengaging parts on the cover and screw valve whereby rotary movement of the cover will adjust the valve. 120

6. In an oil cup, a receptacle, a removable cover therefor, a screw valve for permitting flow of oil from the receptacle, said cover having a flat walled recess in its lower face, said valve having parts shaped to fit said 130

recess, and spring devices for retaining said cover on the receptacle and securing the valve in adjusted position.

7. In an oil cup, a receptacle, a removable cover therefor, a screw valve for permitting flow of oil from said receptacle, a shoulder on the stem of said valve, a plate slidable vertically on said valve a coil spring between said plate and shoulder, a link connection between said plate and cover to retain the cover on the receptacle, and interengaging parts on the valve stem and cover whereby movement of the cover will adjust the valve.
- 10 8. In an oil cup, a receptacle, a removable cover therefor, a screw valve for permitting flow of oil from the receptacle, said cover having a flat walled recess in its lower face, the stem of said valve being

shaped to fit said recess whereby movement 20 of the cover will adjust said valve, and a spring connection between parts of the valve and the cover to retain the latter on said receptacle.

9. In an oil cup, a receptacle, a removable 25 cover therefor, a screw valve for permitting flow of oil from said receptacle, coacting parts on said cover and valve whereby movement of said cover will adjust the valve, means for retaining the cover on the receptacle, and a spring arm on said valve having a portion engaging the wall of said receptacle to prevent accidental shifting of the valve.

In testimony whereof I have hereunto set 35 my hand.

WILLIAM HENRY HART.
